RETRACTING SYSTEM FOR OIL BURNERS

Raymond B. Plass, Berkeley, and Harry K. Winters, San Francisco, Calif., assignors to Ray Oil Burner Co., San Francisco, Calif., a corporation of California

Application August 24, 1951, Serial No. 243,548

3 Claims. (Cl. 158—36)

1

This invention relates to retracting systems operable upon the shutting down of an oil burner to remove the oil from the burner tube and from all the conduits between the burner tip and the shut-off valve.

There are various disadvantages which result from permitting oil to remain in the burner tube and adjacent conduits when a burner is shut down such, for example, as the continued burning of such oil in the atomizing cup and nozzle, and the undesirable viscosity of the oil when it cools particularly where heavier oils of the type that must be preheated are used. These and other disadvantages are well-known in the art and various types of oil retracting systems have been designed and are in use for this purpose.

It is the object of the present invention to provide an improved retracting system for oil burners which is simple and inexpensive in design and positive in operation. A further object of the invention is to provide such a system which avoids the use of small orifices subject to becoming clogged by heavy or dirty oil, and which acts instantly upon the burner being shut down to prevent delivery of further oil toward the nozzle. Further and more specific objects and advantages of the invention and the manner in which it is carried into practice are set forth in detail in the following specification wherein reference is made to the accompanying drawings.

In the drawings:

Fig. 1 is a schematic view of an oil retracting system embodying the present invention.

Fig. 2 is a fragmentary detail of a portion of a pressure regulating valve which forms a part of the system, and

Fig. 3 is a central vertical sectional view of a cylinder with a spring actuated and pressure controlled plunger which provides the retracting action.

In Fig. 1 of the drawings, a burner is schematically illustrated at 10 as supplied with oil through a main pipe 11 and branch pipe 12. A pump 13 driven by a motor 14 withdraws oil from any suitable source of supply not shown and directs it to the burner 10. The motor is energized by an electric circuit including conductors shown at 15 which circuit also controls a magnetically actuated shut-off valve 16. A control switch 17 in this circuit serves to start the motor and open the valve simultaneously and conversely to permit closing of the valve 16 instantly when the motor is deenergized.

The volume of flow to the burner is regulated by a reducing valve 18 which being in the nature of a restriction in the line 11 creates a pressure

2

in that line between the valve 18 and the pump which is higher than the pressure upon the opposite side in the pipe leading to the burner 10. Any excessive pressure thus created is relieved 5 through a return line 19 in which a spring actuated pressure regulating valve 20 is disposed. The valve 20 is by-passed for limited flow of oil as by a conduit illustrated at 21 in Fig. 1 or preferably as shown in Fig. 2 where a valve disc is 10 shown at 22 as having a notch or groove 23 formed in its edge to permit the flow of limited quantity of oil even though the valve is in its closed position. The groove 23 constitutes a restricted orifice ordinarily to be avoided in the system but is not 15 undesirable because it is of the self cleaning type being thoroughly flushed with oil each time the regulating valve opens so that the accumulation of dirt or heavy components is avoided. A retractor cylinder is shown at 24 in Figs. 1 and 3 20 as having a piston 25 therein urged toward the right by a spring 26 in a spring chamber 26a. The piston 25 is self-guided by means of an extension 27 thereon engageable with the interior of a reduced cylindrical portion or pressure chamber 28a of the cylinder as indicated at 28. Slots such as shown at 29 may be provided in the perimeter of the extension 27 to permit the pressure of oil to be exerted against substantially the 25 entire surface of one side of the piston. A conduit 30 forms a communication between the return line 19 and the end of the interior of the cylinder 24 forming the pressure chamber 28a. In a preferred form of the invention the conduit 30 connects with the bottom of the cylinder as 30 shown in Fig. 1 so that dirt or other solids are 35 drained from the cylinder each time that the piston moves to the right. At its opposite end, the spring chamber 26a of the cylinder 24 is connected with the return line 19 beyond the valve 20 by a conduit 31 in which is included a spring 35 pressed check valve 32, which valve is shown in Fig. 3 as being included in the structure of the cylinder 24. A passage 32a is provided in the bottom of the cylinder 24 which connects the conduit 31 with the spring chamber 26a. Since 40 the passage 32a is made up of intersecting bores one of which extends through the cylinder wall, a plug 24a closes the opening and provides access to the passage in the event that cleaning thereof 45 is necessary. A draw-off conduit 33 communicates the chamber 26a of the cylinder 24 with the burner 10 and includes a check valve 35 which 50 opens toward the chamber 26a, which valve 35 is shown in Figure 3 as being included in the structure 55 of the cylinder 24.

In operation the burner is started by closing the

circuit 15 to start the pump and open the valve 16. Pressure produced by valve 18 in the return line 19 which, as previously stated, is higher than that on the burner side of the valve, enters the cylinder 24 and urges the piston therein toward the left against the pressure of spring 26 and the piston remains in this leftward position as long as the burner continues to operate, any oil in the spring chamber having been forced outwardly and returned to the source of supply by means of the conduit 31. When the burner is shut down as by opening of the switch 41, oil pressure in the return line 19 is reduced and the spring 26 urges the piston toward the right. The oil in the right hand side of the cylinder escaping through line 30 and the bypass 21 which is shown as the slot 23 in Fig. 2. This tends to create a vacuum in the spring chamber 26a of the cylinder and consequently draws oil away from the burner 10 and by way of and from conduits 12 and 33. This oil remains in the spring chamber until the burner is again started.

One of the advantages of the present invention is that oil pressure is provided for biasing the piston 25 against the force of a spring 26 without passing oil in a continuous flow through any part of the cylinder. Thus dirt or other solids contained by the oil are not deposited at any point where they might interfere with the smooth operation of movable parts. An advantage of the cylinder and piston construction illustrated in Fig. 3 results from the fact that the piston is effective throughout its entire stroke for performing its retracting function. Furthermore retraction of oil from the burner commences instantaneously upon the burner being shut off because the failure of pressure in the return line 19 is immediately accompanied by rightward movement of the piston 25.

We claim:

1. In an oil burner system including a burner, a pipe line for conducting oil to the burner and means for feeding the oil under pressure to the burner through said line; a shut-off valve in said line between the feeding means and the burner operating to close the line upon cessation of operation of said feeding means, a piston cylinder,

a pressure reducing valve between the shut-off valve and the feeding means, a piston in the cylinder dividing the same into two non-communicating chambers, spring means in one chamber constantly urging movement of the piston into the other chamber, a draw-off pipe line forming a communication conduit between the first pipe line on the burner side of said shut-off valve and said one chamber, a check valve in said draw-off line permitting flow only to said one chamber, a lead-off pipe line communicating with and leading from said one chamber, check valve means in said lead-off line permitting flow only from said one chamber, means operating in said other chamber against said piston in response to pressure in the first pipe line between the oil feeding means and the pressure reducing valve to move the piston into said one chamber against pressure therein opposing such movement, and means for exhausting fluid from said other chamber when the piston is urged thereinto by said spring, said spring reacting upon failure of said pressure and closing of said shut-off valve to reversely move the piston to retract oil from the burner through said draw-off pipe line.

2. The invention according to claim 1, wherein the penultimate means comprises a pipe providing a communicating line between the said other chamber and the first pipe line, and the last means comprises a pipe providing an oil lead-off from said other chamber and a pressure-bleed valve in the last named pipe.

3. The invention according to claim 2, wherein the first lead-off pipe line communicates with the last named lead-off pipe line on the side of the pressure-bleed valve remote from said other chamber.
